(57) CLAIM

We claim the ornamental design for a cart for exhibiting audio/visual devices or the like, as shown and described.

DESCRIPTION

FIG. 1 is a perspective view of a cart for exhibiting audio/visual devices or the like showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is top plan view thereof; and,

FIG. 7 is a bottom plan view thereof.

The broken lines shown are for illustrative purposes only and form no part of the claimed design.

The cart is shown broken away in some areas to indicate that no specific length or height is claimed.
